UNITED STATES PATENT OFFICE.

RAYMOND M. KELLY, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

DISTILLATION APPARATUS.

Application filed August 7, 1920. Serial No. 401,832.

To all whom it may concern:

Be it known that I, RAYMOND M. KELLY, a citizen of the United States, residing at Pittsburgh, in the county of Allegheny and 5 State of Pennsylvania, have invented a new and useful Improvement in Distillation Apparatus, of which the following is a full, clear, and exact description.

The present invention relates broadly to 10 distillation apparatus, and more particularly to apparatus of this character for making pure or mixed distillates from washed benzol.

The principal object of the present invention is to provide a distillation apparatus comprising a still, and a dephlegmator with improved means for decreasing operating expense and increasing the period of use of the apparatus.

20 Another object of the invention is to provide an apparatus of this type with means for by-passing the vapors from the still column around the dephlegmator when mixed distillates are being made, to thereby 25 avoid undue wear on the dephlegmator.

Still another object of the invention is to accomplish such by-passing of the vapors by means of a separable section having permanent deflecting means therein dividing the 30 interior into independent chambers having exterior communicating connections.

A still further object of the invention is to provide means for insuring the return of the condensates from the dephlegmator.

35 The foregoing and other objects, together with their attendant advantages, will be apparent as the invention becomes better understood by reference to the accompanying specification and drawings forming a part 40 thereof, it being premised that changes may be made in the various details and the manner of operation within the scope of the appended claims without departing from the spirit of the invention.

45 Figure 1 is a side view, partly broken away, of the apparatus, and

Figure 2 is an end view of the construction shown in Figure 1.

With benzol distillation apparatus of the 50 type ordinarily employed for producing either pure or mixed distillates from washed benzol, the vapors from the still are conducted through a dephlegmator, the outlet of which leads to a suitable condensing apparatus. As will be readily understood by

any one skilled in this art, the usual modern benzol still is provided with a retort in which the primary vaporization of the charge takes place and a fractionating column in which some separation of the more volatile from the less volatile constituents takes place. With such a construction the dephlegmator is used irrespective of the product being made. In actual practice it has been found, however, 65 that in making mixed distillates such as motor fuel, the dephlegmator is not essential. The present invention relates to means for by-passing the vapors around the dephlegmator when mixed distillates of this 70 character are being formed to thereby decrease the wear on the dephlegmator which is one of the most expensive units of the apparatus. At the same time, it is desirable to provide means for readily conducting the 75 vapors through the dephlegmator when it is desired to make pure benzine, toluene and the like.

Referring more particularly to the drawings, there is illustrated the upper part of 80 a distilling apparatus. The retort portion of the still is not shown, and reference numeral 2 indicates the fractionating column constructed in sections, as is customary in making the columns of benzol stills. The 85 top of the column is provided with a connecting section 4. The dephlegmator 5, which is of the usual construction employed in benzol-distilling apparatus, is carried and supported on the top of the still column. A 90 separable section 7 is interposed between the still column 2 and the dephlegmator 5, the separable section 7 being carried on the connecting section 4 of the still column and supporting the dephlegmator through a dephlegmator-supporting section 8. The section 7 is made separable, so that it may be applied to the usual benzol stills, which as now constructed, have the dephlegmator supported directly on top of the still column. 100

A bypass 6 is provided around the dephlegmator. The apparatus is arranged so that the vapors rising through the still column may be conducted either through the dephlegmator 5 or around the dephlegmator through the bypass 6. 105

While the dephlegmator may be of any desired construction, it is illustrated as the standard dephlegmator for benzol-distilling apparatus, provided with the usual pipes 9 110

for the circulation of water or other cooling medium, and the intermediate baffles 10.

It will be apparent that by regulating the circulation of water through the dephlegmator, the composition of the vapors from the still may be evenly controlled so that a pure product is delivered through the outlet 11 for subsequent condensation. The section 7 is preferably provided with an inclined partition 12 extending entirely across the passageway through the section to divide the interior thereof into upper and lower chambers 14 and 15, respectively. A pipe 16 communicates at one end with the lower chamber 15 and at its other end with the by-pass 6, and a second pipe 17 extends from the by-pass into the upper chamber 14. This second pipe is preferably provided with a control valve 18 and the by-pass 6 and dephlegmator outlet 11 may also be respectively provided with similar valves 19 and 20.

From the foregoing description it will be apparent that with the apparatus in operation, if the valves 18 and 20 are open and the valve 19 closed, the vapors will be conducted from the still column into the lower chamber 15 and thence through the pipes 16 and 17, respectively, into the upper chamber 14 communicating directly with the dephlegmator. These vapors having been acted upon by the dephlegmator, will pass through the outlet 11 to a suitable condensing apparatus for the making of pure products.

On the other hand, if it is desired to form mixed distillates, the valves 18 and 20 are closed and the valve 19 opened so that the vapors from the column are conducted from the lower chamber 15 through the pipe 16 directly into the dephlegmator by-pass. By reason of this operation, wear on the dephlegmator during the making of mixed distillates is entirely eliminated.

The inclination given to the partition 12 has been found desirable as it tends to conduct some of the condensates from the dephlegmator back into the still column. A supplemental means for this purpose is preferably provided, however, and is illustrated as comprising a return pipe 21 communicating with a suitable trap 22 in the dephlegmator supporting section 8, and sealed at its other end in the pipe 24. From this pipe the condensates enter one of the sections of the still column through a connection 25.

The advantages of the present invention arise from a construction in which excessive wear on the dephlegmator is eliminated, and in which the by-passing of the vapors around the dephlegmator is accomplished by an intermediate solid partition whereby the use of internal valves in the intermediate section is eliminated.

A further advantage resides in the re-

movable nature of the intermediate section whereby the standard distilling apparatus as now manufactured may be readily equipped with the improvements described.

The term "partition" as used in the claims is definitive of any wall, closure or deflecting plate functioning to prevent the through passage of vapors.

I claim:

1. A distillation apparatus comprising a still column, a dephlegmator provided with means for circulating a cooling medium therethrough, a dephlegmator bypass, a removable section between the still column and dephlegmator serving to support the dephlegmator on the still column, a partition extending transversely in said section dividing the interior thereof into independent chambers, and pipe connections to the removable section for conducting the vapors from the still column either around the partition into the dephlegmator or into the dephlegmator bypass, substantially as described.

2. A distillation apparatus comprising a still column, a dephlegmator provided with means for circulating a cooling medium therethrough, a dephlegmator bypass, a removable section between the still column and dephlegmator serving to support the dephlegmator on the still column, a partition extending transversely of said section dividing the interior thereof into independent chambers, and piping connections entering the chambers on opposite sides of the partition and arranged for conducting the vapors from the still column either around the partition into the dephlegmator or into the dephlegmator bypass, substantially as described.

3. A distillation apparatus, comprising a still column, a dephlegmator provided with means for circulating a cooling medium therethrough, a dephlegmator bypass, a removable section between the still column and dephlegmator serving to support the dephlegmator on the still column, a partition extending transversely of said section dividing the interior thereof into independent chambers, and piping connections entering the chambers on opposite sides of the partition and arranged for conducting the vapors from the still column either around the partition into the dephlegmator or into the dephlegmator bypass, said piping connections serving to drain condensate from the chamber above the partition, substantially as described.

4. A distillation apparatus comprising a still column, a dephlegmator provided with means for circulating a cooling medium therethrough, a dephlegmator outlet, a removable section between the still column and dephlegmator and serving to support the dephlegmator on the still column, a

partition extending across said section dividing it into upper and lower chambers, a dephlegmator bypass pipe opening into the dephlegmator outlet, and two pipes connected with the dephlegmator bypass and communicating respectively with the upper and lower chambers in the removable section, whereby the vapors may be led either around the partition into the dephlegmator or to the dephlegmator bypass entirely around the dephlegmator, substantially as described.

5. A distillation apparatus comprising a still column, a dephlegmator provided with means for circulating a cooling medium therethrough, a valved outlet for the dephlegmator, a removable section between the still column and dephlegmator and serving

to support the dephlegmator on the still column, a partition extending transversely of said section dividing it into upper and lower chambers, a valved bypass opening into the dephlegmator outlet beyond its valve, and two connections from the bypass communicating respectively with the upper and lower chambers of the removable section, the connection to the upper chamber being provided with a valve, whereby the vapors from the still column may be conducted either through the dephlegmator or around the dephlegmator through the bypass, substantially as described.

In testimony whereof, I have hereunto set my hand.

RAYMOND M. KELLY.

partition extending across said section dividing it into upper and lower chambers, a dephlegmator bypass pipe opening into the dephlegmator outlet, and two pipes connected with the dephlegmator bypass and communicating respectively with the upper and lower chambers in the removable section, whereby the vapors may be led either around the partition into the dephlegmator or to the dephlegmator bypass entirely around the dephlegmator, substantially as described.

5. A distillation apparatus comprising a still column, a dephlegmator provided with means for circulating a cooling medium therethrough, a valved outlet for the dephlegmator, a removable section between the still column and dephlegmator and serving

to support the dephlegmator on the still column, a partition extending transversely of said section dividing it into upper and lower chambers, a valved bypass opening into the dephlegmator outlet beyond its valve, and two connections from the bypass communicating respectively with the upper and lower chambers of the removable section, the connection to the upper chamber being provided with a valve, whereby the vapors from the still column may be conducted either through the dephlegmator or around the dephlegmator through the bypass, substantially as described.

In testimony whereof, I have hereunto set my hand.

RAYMOND M. KELLY.

Certificate of Correction.

It is hereby certified that in Letters Patent No. 1,541,227, granted June 9, 1925, upon the application of Raymond M. Kelly, of Pittsburgh, Pennsylvania, for an improvement in "Distillation Apparatus," errors appear in the printed specification requiring correction as follows: Page 1, line 16, after the word "still" insert the words *having a fractionating column*; page 2, line 39, before the word "column" insert the word *still*; and that the said Letters Patent should be read with these corrections therein that the same may conform to the record of the case in the Patent Office.

Signed and sealed this 7th day of July, A. D. 1925.
